UNITED STATES PATENT OFFICE.

DAVID L. DAVIS, OF BROOKLYN, NEW YORK.

DESIGN FOR STATIONERY.

SPECIFICATION forming part of Design No. 13,312, dated September 19, 1882.

Application filed August 22, 1882. Term of patent 34 years.

To all whom it may concern:

Be it known that I, DAVID L. DAVIS, of Brooklyn, in the county of Kings and State of New York, have invented a new and Improved 5 Design for Stationery, of which the following is a full, clear, and exact description.

My design relates to the class of goods known as "mourning stationery," embracing note-paper, cards, and envelopes, which have 10 heretofore been provided with black borderings.

The feature of my design is a crimped or fluted bordering in imitation of and having the appearance of crape or woven material.

15 A in the drawing represents the sheet of paper having a black bordering, *b*, which is crimped or fluted in any suitable manner, so as to have the appearance of a woven-crape border. This feature adds largely to the ornamental appear-

ance of the paper and cards by relieving the 20 dullness and flatness of plain black borders. The flutes may be made more or less irregular and crossed, as fancy or taste may dictate, and may be applied to two or more edges of the sheets, cards, and envelopes. 25

Having thus described my invention, I claim as new and desire to secure by Letters Patent—

1. The design for stationery herein shown and described, which consists in the crimped or fluted bordering or edging. 30

2. The design for stationery herein shown and described, which consists in a black border crimped or fluted in imitation of crape.

DAVID L. DAVIS.
